UNITED STATES PATENT OFFICE.

HARRY JAMES KIRKPATRICK, OF TORONTO, ONTARIO, CANADA, ASSIGNOR TO THE BOECKH COMPANY, LIMITED, OF TORONTO, CANADA.

BRUSH.

1,415,652.

Specification of Letters Patent.

Patented May 9, 1922.

Application filed August 9, 1921. Serial No. 491,030.

To all whom it may concern:

Be it known that I, HARRY JAMES KIRKPATRICK, of the city of Toronto, in the county of York, Province of Ontario, Canada, a subject of the King of Great Britain, have invented certain new and useful Improvements in Brushes, of which the following is a specification.

This invention relates particularly to hand and bath brushes which are constantly subjected to the action of hot water, and my object is to devise a brush which will not be damaged by such treatment, and which will be cleanly, sanitary and durable.

I attain my object by means of the constructions hereinafter described and illustrated in the accompanying drawings in which

Fig. 1 is a longitudinal section of a brush constructed according to my invention;

Fig. 2 a cross section of the same;

Fig. 3 a cross section of the hollow back of the brush as it appears before the insertion of the bristle carrying plate; and

Fig. 4 a perspective view of the complete brush.

In the drawings like numerals of reference indicate corresponding parts in the different figures.

1 is a hollow metal back formed with a rim 2. This back is preferably concaved longitudinally as shown, partly as a feature of an ornamental design and partly to provide an internal shoulder or shoulders 3, for

a purpose which will hereinafter appear. The sides of the back are also concaved longitudinally, partly to provide a finger grip and partly to provide internal shoulders 4 for a purpose which will hereinafter appear.

5 is a metal plate through which are formed a series of rows of holes for the insertion of the tufts of bristles 6. These tufts of bristles extend completely through the holes in the plate 5 and, in a manner well known in the art, are set in a mass of rubber compound 7, which, while originally plastic, sets suitably under the action of a vulcanizing heat. It will be noted, particularly with reference to Fig. 1, that when the plate 5 is inserted within the rim 2 that this mass of rubber compound engages the shoulder 3, while the sides of the plate engage the shoulders 4. The plate carrying the

bristles is thus suitably supported within the back (see Fig. 1) so that, when the edges 8 of the rim of the brush are rolled over, the plate and the bristles are securely held in position in the back. When the plate and the back are so connected water is practically excluded from entering between the plate and the back, and any which does so enter is harmless, as the rubber compound is not in any way injured by the action of hot or cold water or soap.

While I do not limit myself to any particular metal aluminum or an alloy of aluminum will usually be employed.

From the above description, it will be seen that I have devised a brush which will attain the objects of my invention as set out in the preamble to my specification.

What I claim as my invention is:—

1. A brush comprising an oblong metal plate having a plurality of holes therein; bristle tufts extending through said holes; a mass of bristle sealing compound applied to the back of the plate and the inner ends of the tufts of bristles; a sheet metal back having a rim within which the plate is adapted to fit, the back having a central depression stamped longitudinally in its back forming a longitudinal shoulder engageable by the mass of sealing compound and the edge of the rim being turned over the plate to hold it in place.

2. A brush comprising an oblong metal plate having a plurality of holes therein; bristle tufts extending through said holes; a mass of bristle sealing compound applied to the back of the plate and the inner ends of the tufts of bristles; a sheet metal back having a rim within which the plate is adapted to fit, the back having an inwardly pressed groove in each of its longer sides forming internal shoulders engageable by the sides of the back of the plate and the edge of the rim being turned over the plate to hold it in place.

3. A brush comprising an oblong metal plate having a plurality of holes therein; bristle tufts extending through said holes; a mass of bristle sealing compound applied to the back of the plate and the inner ends of the tufts of bristles; a sheet metal back having a rim within which the plate is adapted to fit, the back having a central depression stamped longitudinally in its back

forming a longitudinal shoulder engageable by the mass of sealing compound and having an inwardly pressed groove in each of its longer sides forming internal shoulders engageable by the back of the plate and the edge of the rim being turned over the plate to hold it in place.

Signed at Toronto this 25 day of July 1921.

HARRY JAMES KIRKPATRICK.
